UNITED STATES PATENT OFFICE.

ARTHUR C. VAN HOUWELING, OF PELLA, IOWA.

KEY-SEAT CUTTER.

SPECIFICATION forming part of Letters Patent No. 683,868, dated October 1, 1901.

Application filed March 11, 1901. Serial No. 50,606. (No model.)

To all whom it may concern:

Be it known that I, ARTHUR C. VAN HOUWELING, a citizen of the United States, residing at Pella, in the county of Marion, State 5 of Iowa, have invented certain new and useful Improvements in Key-Seater Attachments for Planing or Shaping Machines, of which the following is a specification.

The objects of my invention are, first, to 10 provide a device of simple, strong, durable, and inexpensive construction that may be readily, quickly, and easily applied to a planer or shaper of the ordinary kind for the purpose of cutting keyways in pulleys, &c.

15 A further object is to provide a device of this class in which the cutting-tool is firmly and immovably held during both the effective and the return strokes, whereby a maximum of accuracy in cutting a key-seat is attained.

20 A further object is to provide simple and automatically-operating means whereby the cutting-tool is relieved upon its return stroke from engagement with the work, so that said cutting edge will not be dulled by travel on 25 its return stroke in engagement with the work.

A further object is to provide a cutting-tool 30 of such shape that when dulled or worn off by constant use it may be sharpened until a considerable portion of the tool has been used up; and my object is, further, to provide a device of this class in which the cutting-tool is firmly held and the adjusting means whereby the depth of cut is determined is entirely 35 independent and separate from the cutting-tool. Hence the depth of cut may be quickly and easily set by the operator at any time without affecting the fastenings of the cutting-tool.

40 My invention consists in certain details in the construction, arrangement, and combination of the various parts of the attachment and in the combination thereof with a planer or shaper, as hereinafter more fully set forth, 45 pointed out in my claims, and illustrated in the accompanying drawings, in which—

Figure 1 shows in side elevation a portion 50 of an ordinary planer or shaper having my attachment applied thereto and showing a pulley on the attachment, said parts being in position for cutting a keyway in said pulley. Fig. 2 shows in perspective that portion

of the attachment connected with the tool-holder of the planer or shaper. Fig. 3 shows a vertical longitudinal sectional view of the 55 mandrel, upon which the work is placed, showing a groove therein of uniform depth. Fig. 4 shows a like view of a modified form in which the groove is tapered, and Fig. 5 shows in side elevation the cutting-tool and 60 its adjusting-wedge.

Referring to the accompanying drawings, I have used the reference-numeral 10 to indicate the frame of the planer or shaper. 11 indicates the table of said machine, upon which 65 the work is usually placed, and 12 indicates the reciprocating carriage, to which the tool-holder 13 is fixed.

My attachment comprises, first, an upright 14, having a forked lower end 15, in which a 70 set-screw 16 is placed. This part 14 is designed to pass through the opening in the tool-holder 13, which is provided for holding the tools used in planing or shaping, and the set-screw 17 serves to hold the parts 14 75 firmly and immovably in position. Above the part 13 a yoke 18 is fixed to the upright 14 to project horizontally therefrom, and the side pieces 19 are fixed to the forward end of this yoke. Between the upper ends of the 80 side pieces 19 is a pivoted block 20, having the central screw-threaded opening designed to admit a screw-threaded rod 21. On the forward end of the rod 21 is a handle 22, and the rear end of said rod is pivotally mounted 85 in a link 23, which link is pivoted to the top of the upright 14. Obviously a manipulation of the handle 22 will force the top ends of the side pieces 19 either toward or away from the upper end of the upright 14. 90

The body of the cutting-tool is indicated by the reference-numeral 24, and it is designed to enter the lower end of the upright 14 and be firmly secured thereto by the set-screw 16. At the forward end of the cutting-tool is the cutting-point, which inclines forwardly and downwardly at 25, the top surface of the cutting-tool being preferably straight and flat. The wedge, whereby the position of the cutting-tool is adjusted, comprises a body 100 portion 26, flat on its underside, except near its forward end, where it is provided with a downwardly and forwardly inclined surface 27. In its body portion is a slot 28 for purposes herein-

after made clear. This cutting-tool-adjusting device is placed above the cutting-tool, and a pin or bolt 29 passes through the lower end of the parts 19 and through the slot 28, and the rear end of the part 26 passes through a rigid arm 30 on the carriage 12, and an extensile coil-spring 31 is placed thereon, with one end in engagement with the part 30 and the other end in engagement with a nut 32, 10 adjustably secured to the rear end of the part 26. By this means the cutting-tool-adjusting device is normally held to the forward limit of its movement, and yet it may move rearwardly a slight distance against the pressure 15 of the spring, said movement being limited by the length of the slot 28.

The means for holding the work comprises a part 33, fixed to the table 11, a support, and a mandrel 34, said mandrel being provided with 20 a longitudinal groove 35 on its under surface. Where the key-seat is to be made straight, the mandrel shown in Fig. 3 is used, and where the key-seat is to be tapered the mandrel shown in Fig. 4 is substituted, it being understood 25 that the travel of the cutting end of the cutting-tool is confined within the limits of the groove 35 in the mandrel 34. A spring 36 is fixed to the top of the table 11 and normally engages the under surface of the cutting-tool to exert a yielding pressure in an upward direction thereupon.

In practical use the attachment may be readily connected with a planer or shaper by placing the upright 14 in the tool-holder of 35 the reciprocating carriage and by placing the part 33 upon the work-table 11. Then when the parts are adjusted and a pulley or the like placed on the mandrel 34 the handle 22 is manipulated to force the parts 26 forwardly or backwardly until the point of the cutting-tool engages the interior of the pulley-hub in proper manner. Then the reciprocating carriage is made to advance, and during its forward movement the cutting- 40 tool will make its first effective movement, the wedge 27 being firmly held in place during this effective movement by the pin or bolt 29 engaging the front surface of the slot 28. During the return stroke the cutting-tool will first move rearwardly until the limit of movement of the pin 29 in the slot 28 has been reached. Then the parts will move rearwardly or on the return stroke together. However, the slight movement permitted by the slot 28 is amply sufficient to relieve the cutting-tool from engagement 45 with the work. Furthermore, the spring 36 serves to elevate the cutting-tool and prevent it from rubbing against the work on its 50 return stroke. When it is desired to cut a tapered key-seat, the mandrel shown in Fig. 4 is substituted for that shown in Fig. 3, and obviously the cutting-tool may be readily sharpened whenever dulled until a consider-

able portion of the tool is used up in this 65 process.

Having thus described my invention, what I claim, and desire to secure by Letters Patent of the United States therefor, is—

1. A key-seating attachment for planers or shapers, comprising a support to be attached to the machine-carriage, a cutting-tool connected with the support, a frame adjustably connected with the support, a wedge carried by said frame, to engage the cutting-tool, means for connecting the wedge to the frame, whereby a limited sliding movement is permitted, a yielding pressure device to normally hold the wedge to one limit of its movement, and a longitudinally-slotted mandrel 80 to receive the work and to permit the wedge and tool to reciprocate in its slot, for the purposes stated.

2. A key-seating attachment for planers or shapers, comprising in combination a support detachably connected with the reciprocating carriage of the machine, a cutting-tool detachably and adjustably fixed to the lower end of said support, to project horizontally, and having its cutting edge inclined 85 forwardly and downwardly, a brace fixed to the support, a frame pivoted to said brace, means for tilting said pivoted frame, a wedge connected with the lower end of the frame, so as to be capable of limited sliding movement with relation to the frame, a spring for normally holding the wedge to its rearward limit of movement, a mandrel having a longitudinal slot and connected with the machine-frame to receive said wedge and cutting-tool, substantially as, and for the purposes stated.

3. A key-seating attachment for planers or shapers, comprising in combination a support detachably connected with the reciprocating carriage of the machine, a cutting-tool detachably and adjustably fixed to the lower end of said support, to project horizontally, and having its cutting edge inclined 105 forwardly and downwardly, a brace fixed to the support, a frame pivoted to said brace, means for tilting said pivoted frame, a wedge connected with the lower end of the frame, so as to be capable of limited sliding movement with relation to the frame, a spring for 110 normally holding the wedge to the rearward limit of movement, a mandrel having a longitudinal slot and connected with the machine-frame to receive said wedge and cutting-tool, and a spring to engage the under 115 surface of the cutting-tool, to normally force it upwardly, substantially as, and for the purposes stated.
